WINDING MECHANISM FOR FORMING YARN OR THREAD PACKAGES.

1,141,894.

Specification of Letters Patent. Patented June 1, 1915.

Application filed July 1, 1912. Serial No. 708,910.

To all whom it may concern:

Be it known that I, JOHN V. CUNNIFF, a citizen of the United States, and a resident of Fall River, in the county of Bristol and 5 State of Massachusetts, have invented an Improvement in Winding Mechanism for Forming Yarn or Thread Packages, of which the following description, in connection with the accompanying drawings, is a 10 specification, like characters on the drawings representing like parts.

This invention relates to winding mechanism for forming yarn or thread packages, and specifically and more particularly to 15 builder mechanism for ring spinning or twisting mechanism.

My present invention herein disclosed is intended to provide mechanism to fulfil the same functions set forth in my co-pending 20 application Serial No. 685,030, but the flexible element, herein a chain, is let off or elongated during the winding operation, and specifically to furnish a single-acting traverse-and-gain controlling mechanism of simple form, to which existing mechanisms can 25 be readily converted and adapted.

In order that the principle of the invention may be readily understood, I have chosen to illustrate that embodiment thereof 30 consisting of builder mechanism for ring spinning frames, that is, a specific application of winding mechanism.

In the drawings,—Figure 1 is a front elevation of one form of builder mechanism for 35 ring spinning frames constituting an embodiment of the invention; Fig. 2 is a plan view of a portion thereof; Fig. 3 is a vertical transverse section of a ring spinning frame having my invention applied thereto; Fig. 4 is a detail, partially in section, of the 40 nut or governing means for the flexible element; Fig. 5 is a side elevation of a portion of a modified form of said mechanism; Fig. 6 is a similar view of a still further modified 45 form thereof; and Fig. 7 is a side elevation representing a different manner of attaching the flexible element to the primary actuator lever.

In yarn or thread winding mechanism to 50 which my invention relates, the coils of yarn are laid along the yarn receiver by effecting a relatively oscillatory movement of a yarn guide and the yarn receiver along the latter for a portion of its length, which movement 55 is generally called the "traverse"; and the

package is built by shifting the path of this relative movement progressively along the axis of the yarn receiver, which shifting is generally termed the "gain". In the formation of such a yarn package a maximum 60 diameter is reached at a point above the lower end thereof due to the co-operative effect of the traverse and the gain; and a portion of the package from its lower end to such point of maximum diameter is 65 termed the "base"; while the conical form resulting at the other end of the yarn package is termed the "chase", or the "taper"; and its terminus the "nose" of the cop.

My invention provides means whereby 70 the package may be wound and formed with efficiency in a winding or spinning or twisting machine; and particularly in a spinning or twisting machine it furnishes means whereby the tension of the yarn in winding may 75 be well controlled and thereby the lay of the yarn benefited. In the formation of the base of the package the invention provides means whereby the successive layers of yarn may be so laid, one over the other, until the 80 full diameter of the package is secured, that each bottom coil of each layer is laid safely up and above the bottom coil of the preceding layer (assuming the yarn receiver to be upright and the yarn to be wound thereon 85 from the bottom upward as in the preferred arrangement of parts of mechanism embodying my invention); and while the mechanism accomplishes this broadly in the formation of the base of the package it may be 90 and in the disclosed embodiment of the invention is arranged to continue the same winding effect throughout the entire length of the package. The feature of the winding is accomplished by increasing the gain 95 and preferably by progressively increasing the gain throughout the formation of the base of the package; throughout the remainder of the package the gain should be such as to maintain the body of the package of 100 substantially uniform diameter. To this end, I may while constantly increasing the traverse throughout the cop, so control the gain as to accomplish this result. This may be effected by providing for an unincreased 105 gain throughout the body of the package above the base, provided the increasing traverse be maintained. Co-operatively with this mechanism for increasing the gain, mechanism is provided to increase the traverse 110

throughout the formation of the base and preferably throughout the formation of the whole package. The result of this increase of traverse is obviously to lay each successive layer of yarn over a slightly greater extent axially of the package; and further, due to the constant speed of the spindle or other yarn receiver, and in ring frames particularly, due further to the constant speed of the feed rolls, if each traverse is effected in the same period of time (which is accomplished by giving the primary controller of the traverse movement a stroke constant in time and distance), the yarn each time will be laid in coils a little more widely separated.

Having reference to the utilization of such a yarn package which involves its unwinding features, the result is that the increasing traverse from base to nose gives reversely a decreasing taper from nose to base, so that the yarn withdrawn by draft axially of the package is drawn from a surface on the package approaching more and more nearly to a surface at right angles to the axis of the package. By this means as the length of yarn extending from the surface wherefrom it is being delivered to the point above the package where draft is being applied to the yarn, tends to increase, and ballooning of the yarn away from the axis of the package tends to increase, this tendency to increased ballooning effect is checked by the yarn drawing from a surface which tends to approach more and more nearly to a flat surface at right angles to the axis of the package, and when the yarn package is in a shuttle this described construction of package checks the tendency of the yarn to balloon out and contact with the sides of the shuttle and therefore tends to decrease breakage. Further, as the base of the cop is reached in the unwinding (and throughout the whole package if and when the increase in gain is established throughout the whole package) each bottom coil of each layer (having been safely laid by means of the increase in gain over and above the bottom coil of the preceding layer) is permitted to be withdrawn without fouling with and tending to slough off the preceding layer. These advantages thus secured in the unwinding are of great practical importance in weaving where the yarn is subjected to quick intermittent draft reaching a speed of from five to ten yards a second.

Inasmuch as each traverse is increased over its predecessor, each traverse advances more at the top of the wind than at the bottom thereof. The effect of the described traverse and gain are to build a yarn package, which at the bottom extends from the surface of the receiver to a maximum diameter without laying the bottom coil of any

wind or traverse on top of or below the bottom coil of the preceding layer or traverse. The slight but continuous incremental increase in the gain throughout at least the base of the package, together with the direct increase in the traverse lays the yarn so uniformly that the base of the yarn package is formed with a straight line constituting a conical bottom in vertical cross section until the maximum diameter of the cop or other yarn package is reached. Such maximum diameter is substantially maintained until the tip of the yarn package is reached. Thus, the increase in traverse and incremental increase in gain are effective to produce and maintain a correct and advantageous form of package.

While I have referred to the increase in the traverse as constant, this term is employed generically or broadly to refer to a preferably regular increase in the traverse, such increase occurring at a certain part of each traverse, or if desired at a certain part of each of a series of traverses. I preferably impart the increase to the traverse and the increase to the gain during the up-stroke of the ring rail and preferably near the end of such up-stroke and terminating with the end of the up-stroke.

Inasmuch as the builder cam employed in the disclosed embodiment of the invention rotates preferably at a constant speed, and inasmuch as the traverse is regularly increased, it follows that the speed of the ring rail is correspondingly increased, and inasmuch as the addition to the traverse and the addition to the gain are imparted in the present embodiment of the invention at or near the end of the up-stroke of the ring rail, it follows that the speed of movement of the ring rail is accelerated each time toward the end of its up-stroke,—that is, when the yarn is winding upon the nose of the yarn package.

Referring more particularly to the drawings, and first to the construction shown in Figs. 1 to 4 thereof, the frame of a winding mechanism is represented at 1. This winding mechanism may be employed for winding yarn or thread either with or without spinning the same. In the present embodiment of the invention, I have disclosed essential elements of the builder motion of a spinning or twisting frame. The builder cam is indicated at 2 in Fig. 3, it being fast upon a shaft 3 supported in the frame and driven at a preferably constant speed, in any suitable manner, in the direction of the arrow, as from a worm shaft driven by sprocket gearing from the main drive shaft of the spinning frame. The shaft 3 may be driven at a higher rate of speed than heretofore without changing the speed at which the drawing rolls and the spindles are driven.

The spindle rail is indicated at 4, the box rail at 5, both being fixedly supported on the framing 1, the spindles at 6, and the ring rail at 7, the latter preferably carrying the usual spinning rings not shown. The spindles 6 are driven by a band 8 from a drum 9 upon a shaft 10 rotated in any suitable manner. These parts are preferably of usual formation and construction, the 10 spindles 6 being continuously rotated in one direction and the yarn being delivered thereto by the usual sets of drawing rolls, not shown.

The spindles 6 or suitable bobbins or 15 paper or other tubes receivable thereon constitute constantly rotating yarn receivers and the ring rail constitutes one form of yarn guide traversable lengthwise of the yarn receivers.

20 Suitably mounted in the framing of the machine upon a stud or pivot 11 is an actuator lever or builder lever 12 having a constant stroke imparted thereto by the builder cam 2. This builder lever is essentially a 25 guided movable element to carry the chain, and any suitable device may be substituted therefor to accomplish the desired result. The said lever is arranged transversely of the winding or spinning frame as indicated 30 in Fig. 3. The yarn guide or ring rail 7 is provided with a suitable number of rods or pokers 13 constituting the yarn guide holding means. Between the actuator or builder lever 12 and said yarn guide holding means 35 I provide certain coöperating, connecting and governing devices. In the present embodiment of the invention, these devices comprise a flexible element shown as a chain 14, governing means on the lever 12 active 40 upon said flexible element to move the bearing portion thereof on said lever gradually and by increments outward from the fulcrum of the lever and a second oscillating or pivoted member positively connected to 45 said flexible element and having a sliding connection with the said yarn guide holding means 13. These coöperating, connecting and governing devices are so interconnected as simultaneously to increase the 50 effective length of said flexible element and to advance said yarn guide along the yarn receiver by increasing increments, coincidentally with an undiminished incremental outward movement of the bearing through- 55 out the formation of the base of the package and if desired throughout the formation of the entire package. In the precise embodiment herein shown, the let-off of the flexible element is secured by moving a traveler nut 60 in a direction away from the bight of the flexible element where engaging the actuator lever, so that coincidently with the let-off of said flexible element the bearing there- 65 of on said lever is moved outwardly from the fulcrum thereof to secure the desired in- crease of traverse. With the flexible element attached and controlled in this manner, however, fixed incremental movement of the traveler nut will not give a progressively increasing let-off of the flexible element; and since the flexible element constitutes part of the connecting and governing devices between the actuator lever and the yarn guide holding means, and it is desired to secure a progressive advance of the lat- 70 ter, at least throughout the formation of the base of the package, so as to obtain a progressively increasing gain, the other coöperative devices co-active with said flexible element to govern the movement of said yarn 75 guide holding means are herein arranged and connected so that coöperatively such desired progressively increasing advance of said holding means is secured.

The flexible element 14 is connected at 80 one end to a hook 15 upon a bearing 16 supported upon the lever 12 and wherein is rotatably mounted the unthreaded portion of a threaded shaft or screw 17. Upon the screw 17 is mounted a nut 18 carrying a 85 sheave or pulley 19 about which the chain 14 passes, thus forming a bight therein. The said nut constitutes a second bearing for the screw 17. The nut 18 constitutes one 90 form of means that may be employed by me 95 in carrying out my invention, to move the bight forming means toward the open part of the bight, to effect let-off of the flexible element. I am not limited to such disclosed 100 form of means.

I have herein represented the flexible element or chain 14 as passing upwardly and thence about a guiding sheave 20 rotatably supported in a bracket 21 secured to some 105 suitable part of the framing of the mechanism. The flexible element 14 thence extends longitudinally of the framing or mechanism to the second oscillating or pivoted member to which I have referred and which is herein shown as a bell crank lever 22 mounted upon a stud or rock shaft 23 and having an arm 24 provided if desired 110 at its outer end with a roller 25 adapted to take under the foot 25' of the yarn guide holding means 13. The connection between the lever 22 and the yarn guide holding means 13 is herein disclosed as a sliding one, and may be of any suitable type involving 115 intermeshing teeth if desired. The lever 22 is provided with an arm 26 to the outer end 120 of which is connected a rod 27 extending longitudinally of the framing and connected to one or more other levers preferably generally similar to the lever 22 and co-acting 125 with other yarn guiding holding means 13. The number of levers and yarn guide holding means, of course, varies with the design and structure of the mechanism.

The arm 26 of the lever 22 is provided 130 with a curved extension 28, the flexible ele-

ment receiving surface of which constitutes a true arc struck from the axis of the lever 22. The end of the chain 14 is represented as provided with a screw eye 29 secured to the end 30 of the extension 28. The lever 22 is provided with a third arm 31 having thereon a cotinterweight 32, the construction of parts being such that as the flexible element or chain 14 is let off from the actuator lever 12, the lever 22 moves about its axis in a clockwise direction to elevate the ring rail or yarn guide 7. The said lever 22 oscillates about its axis by reason of the constant stroke imparted to the actuator lever 12, to which the lever 22 is connected as described by the flexible element or chain 14.

In order to move the nut 18 outward upon the actuator or builder lever 12, that is, in the direction away from the bight of the chain of the flexible element 14 passing about the sheave 19 carried by the nut 18, or, in other words, toward the open part of the bight of the chain, I may provide any suitable mechanism. Herein for the purpose I have represented a ratchet 33 fast upon the outer end of the screw 17 and a sleeve 34 loosely mounted upon the screw 17 adjacent the ratchet and between it and the bearing 16. The sleeve 34 is provided with or has formed therewith a lever having an arm 35, to which is pivoted a pawl 36 taking into the teeth of the ratchet 33 and a second arm 37 to which is connected by a slot and pin connection 38 a rod 39 having a threaded end 40 passing loosely through an opening in the flange 44 of a bracket 41 bolted to the box rail 5. Upon the threaded portion of the rod 39 are nuts 42, 43, and co-acting lock nuts may be provided if desired. The actuator or builder lever 14 is periodically depressed by the cam 2 and periodically rises because of the counterweight 32 upon the lever 22. Near the termination of each rising movement of the lever 12, the nut 43 upon the threaded rod 39 is brought into engagement with the lower face of the flange 44 of the bracket 41, and hence further upward movement of the said rod 39 is prevented. Inasmuch, however, as the lever 12 continues its upward movement, the pawl 36 compels the clockwise rotation of the ratchet 33, and hence rotates the screw 17 incrementally in such a direction as incrementally to advance the nut 18 outward along said screw 17 and the lever 12. The extent of this rotative movement of the ratchet 33 may be varied by varying the position of the nut 43 upon the rod 39. Upon the downward movement of the lever 12, the nut 42 on the threaded rod 39 contacts with the upper face of the flange 44 of the bracket 41, and hence moves the pawl 36 in a counterclockwise direction along the teeth of the ratchet 33. It is evident that the nut 18 is periodi-

cally moved outward along the screw 17 at or substantially at the termination of each upward movement of the actuator lever 12, and hence when the yarn guide 7 is substantially at the top of its traverse. 70

Inasmuch as the traverse is controlled by the nut 18 and inasmuch as the gain is controlled in part by said nut 18, it is evident that I have in this embodiment of the invention provided a single-acting traverse 75 and gain controlling mechanism. In the operation of the mechanism, the traverse is increased by the gradual outward movement of the bearing of the chain, that is, by the described movement of the nut 18, 80 and the gain, throughout the base at least of the passage, is increased by the co-operation of the several described instrumentalities.

In the mechanism shown in my co-pending application Serial No. 685,030 above referred to, the gain is gradually increased by the outward movement of the bearing of the flexible element or chain on the builder element, and the gain is effected by the progressive shortening of the flexible element and by the action of the said flexible element on the second pivoted lever, and the action of the latter on the guide holding means whereby incremental rotation of the 90 second pivoted lever is effected by the said flexible element, giving an increasing, incremental, right line movement of the yarn guide holding means. In accordance with my present invention, however, the gain, 100 which is a progressively increasing gain throughout at least the base of the yarn package, is effected, first, by progressively decreasing the amount of let off of the flexible element or chain instead of by a take up of the 105 chain as described in my said earlier application, and second by the co-operative action of the said flexible element 14, the second pivoted lever 22 and the guide holding means 13, whereby fixed incremental rotation of the said second pivoted lever 22, as 110 permitted by the said flexible member 14, gives an increasing incremental advance of the guide holding means to such an extent that this is dominant over the decrease in 115 the let off in the flexible element as effected by the movement of the nut 18.

During the building of the yarn or thread package, the lever 22 is not only constantly oscillated about its axis 23, but its arcs of 120 movement constantly advance, in a clockwise direction. At the commencement of the operation the arm 24 of the lever 22 is at its lower position and the translation in a clockwise direction of the arcs of movement of said lever 22 continually advances the lowermost position of the arm 24 of said lever until the said arm is horizontal at the downward limit of its arc movement. This advancing movement of the arm 24 130

to the horizontal gives an increasing incremental advance of the guide holding means. As the advance in the position of the downward limit of the lever arm 24 continues and 5 rises above the horizontal, the incremental advance of the guide holding means becomes progressively less, or in other words from such horizontal position of the lever arm 24 onward, the gain is a progressively 10 decreasing increase or an unincreased gain after the base of the package has been completed. The character of the gain after the completion of the base should be such as, in conjunction with the described increasing 15 traverse, to build a package, the body of which is of substantially uniform diameter. Throughout the base at least of the package the gain is a progressively increasing one. Within the scope of my invention 20 the gain may be rendered a progressively increasing one throughout the entire package.

In that form of the invention shown in Figs. 1 to 4, a constant rotation or advance 25 of the lever 22 gives an increasing advance or gain up to the described horizontal position of the lever arm 24, inasmuch as the extension 28 of said lever 22 is a true arc struck from the axis 23 of said lever. By 30 varying the shape of said extension 28, however, I may vary the character of gain.

In Fig. 5, I have represented the lever 22' as having arms 24', 26'. The latter is provided with an extension 45 that is not a 35 true arc struck from the axis of the lever 22', but is an arc somewhat flattened along the part 46 thereof, so that as the lever 22' is advanced in a clockwise direction, the amount of chain taken up thereby upon the 40 extension 45 progressively decreases, thus compensating for the decrease in the progressive increase of the gain that otherwise would occur after the arm 24' of the lever 22 had reached the horizontal as its lowermost limit of its arc movement.

In Fig. 6, I have represented a lever 22'' having arms 24'' and 26''. The latter is provided with an extension 47 that is not wholly a true arc struck from the axis of 50 the lever 22'', but is a curve, the left hand portion 48 whereof (viewing Fig. 6) is at an increasingly greater radial distance from the axis of the lever 22'' than the right hand portion thereof, which is a true arc struck from said axis. As the lever 22'' is advanced in a clockwise direction, the amount of chain taken up thereby from the extension 48 progressively increases, thus somewhat further decreasing the gain after 55 the arm 24'' has reached the horizontal as the lowermost limit of its arc of movement. It is evident that by varying the curve 48, the gain may be a progressively decreasing increase of the desired extent, or that an unincreased gain may be secured in or through 60

the body of the package, or that any suitable effect may be secured, which in conjunction with the described increase in traverse, will result in a package of substantially uniform diameter throughout the body thereof.

In Fig. 7, I have represented further means for modifying or varying the amount of chain let off by the movement of the nut 18 outward along the lever 12. In said figure, the nut 18 and its pulley 19 are so 70 located that the portion of the chain 14 between the guide pulley 19 of said nut and the guide pulley 20' upon the framing of the machine is substantially vertical when said nut 18 is at or near the inward limit of its movement along the screw 17 instead of at an acute angle as represented in Fig. 3, though suitable variation of this construction may be made. The lever 12 at its outer end is provided with a downward extension 75 49 having a hook 50 to which the end of the chain 14 is connected. The hook 50 may be secured in or at any one of the sockets or holes 51. The lever 12 receives an oscillatory movement in the manner previously described and as the nut 18 moves outward along the screw 17, there is but very little change in the length of chain between the nut 19 and the guide pulley 20'. The amount of chain, however, between the nut 80 19 and the hook 50 is continually diminishing, so that the resultant action may be a let-off of the chain which effects a progressively decreasing increase in the gain. It will be observed that the hook 50 may be 85 100 and is shown as so positioned that the guide pulley 19 does not move parallel with the portion of the chain passing around said pulley to the hook 50. Therefore the amount of chain let off for a given movement of the pulley 19 will be decreased as the hook 50 is approached thereby. The effect of this is that for a given let-off of the chain necessary to give the total gain (which determines the length of the finished cop), 90 105 110 the pulley 19 can, if desired, be moved a greater distance, which means a greater increase in traverse between the beginning and ending of the building operation.

An advantage of the particular form of 115 mechanism herein shown whereby the gain is had by a let-off of the flexible element is that it provides mechanism of great simplicity to which many existing forms can be readily converted and which will give 120 substantially the same results in bobbins or cops of usual lengths as is secured by the form of mechanism shown in my said earlier application, Serial No. 685,030.

Instead of employing a guiding sheave 20, 125 I may lead the flexible element 14 directly from the actuator or builder lever 12 to a drum or disk concentrically mounted on or with the axis of the second lever 22, thus securing the same result as that disclosed in 130

said application. The intermediate sheave 20 is, however, preferably employed to obtain a better working mechanism and to obtain the best location of the directly operating parts.

Having thus described one illustrative embodiment of my invention, I desire it to be understood that although specific terms are employed, they are used in a generic and descriptive sense and not for purposes of limitation, the scope of the invention being set forth in the following claims.

Claims:

1. Winding mechanism for forming yarn packages comprising in combination, a rotating yarn receiver and a yarn guide traversable lengthwise thereof, a traverse and gain controlling mechanism for the guide, said mechanism embodying an actuator lever having a to and fro stroke, yarn guide holding means, and coöperating connecting and governing devices on said lever and between the same and said means, said devices comprising a flexible element operatively connected at one end portion to the yarn guide holding means and having its other end portion attached to said lever at a fixed distance from the pivot thereof, means on said lever forming a bight in the flexible element, and means to move said bight forming means incrementally toward the point of attachment of the flexible element to said lever during the building operation.
2. Winding mechanism for forming yarn packages comprising in combination, a rotating yarn receiver and a yarn guide traversable lengthwise thereof, a traverse and gain controlling mechanism for the guide, said mechanism embodying an actuator lever having a to and fro stroke, yarn guide holding means, and coöperating connecting and governing devices on said lever and between the same and said means, the said devices comprising a flexible element connected at one end portion to the yarn guide holding means and connected at its other end portion to said lever, means on said lever forming a bight in the flexible element, and means to move said bight forming means during the building operation toward the open part of the bight.
3. Winding mechanism for forming yarn packages comprising in combination, a constantly rotating yarn receiver and a yarn guide traversable lengthwise thereof, a traverse and gain controlling mechanism for the guide, said mechanism embodying an actuator lever having a to and fro stroke, yarn guide holding means, and coöperating connecting and governing devices on said lever and between the same and said means, the said devices comprising a flexible element operatively connected at one end portion to said yarn guide holding means and attached at its other end portion to said

lever, means on the lever forming a bight in the flexible element, and means to move the bight forming means by uniform increments during the building operation in a direction to effect a let-off of said flexible element from said actuator lever.

4. Winding mechanism for forming yarn packages comprising in combination, a constantly rotating yarn receiver and a yarn guide traversable lengthwise thereof, a traverse and gain controlling mechanism for the guide, said mechanism embodying an actuator lever having a to and fro stroke, yarn guide holding means, and coöperating connecting and governing devices on said lever and between the same and said means, the said devices comprising a flexible element operatively connected at one end portion to said yarn guide holding means and fixedly connected at its other end portion to said lever at a fixed distance from the pivot thereof, means on said lever forming a bight in the flexible element, and means to move said bight forming means during the building operation by increments toward the open part of the bight.

5. Winding mechanism for forming yarn packages comprising in combination with a constantly rotating yarn receiver and a yarn guide traversable lengthwise thereof, a traverse and gain controlling mechanism for the guide, said mechanism embodying an actuator lever having a to and fro stroke, a bell crank lever, a poker arm operatively connected thereto, a flexible element operatively connected at one end portion to said bell crank lever and at its other end portion to said actuator lever at a fixed distance from the pivot of the latter, means on said actuator lever to form a bight in the flexible element, and means to move said bight forming means by increments during the building operation toward the open part of said bight.

6. Winding mechanism for forming yarn packages comprising in combination, a constantly rotating yarn receiver and a yarn guide traversable lengthwise thereof, a traverse and gain controlling mechanism for the guide, said mechanism embodying a movable member, means to impart a to and fro stroke thereto, yarn guide holding means and coöperating connecting and governing devices on said member and between the same and said yarn guide holding means, the said devices comprising a flexible element operatively connected at one end portion to said yarn guide holding means and at its other end portion to said movable member, means on said member forming a bight in the flexible element, and means to move said bight forming means bodily during the building operation by increments in a direction to effect let-off of said flexible element from said movable member.

7. Winding mechanism for forming yarn packages comprising in combination, a constantly rotating yarn receiver and a yarn guide traversable lengthwise thereof, a traverse and gain controlling mechanism for the guide, said mechanism embodying a movable member, means to impart a to and fro stroke thereto, yarn guide holding means and coöperating connecting and governing devices on said member and between the same and said yarn guide holding means, the said devices comprising a flexible element operatively connected at one end portion to said yarn guide holding means and at its other end portion attached to said member at a fixed distance from the ends thereof, means on said member forming a bight in the flexible element, and means to move said bight forming means during the building operation toward the open part of the bight.

8. Winding mechanism for forming yarn packages comprising in combination, a constantly rotating yarn receiver and a yarn guide traversable lengthwise thereof, a traverse and gain controlling mechanism for the guide, said mechanism embodying a movable member, means to impart a to and fro stroke thereto, yarn guide holding means and coöperating connecting and governing devices on said member and between the same and said yarn guide holding means, the said devices comprising a flexible element operatively connected at one end portion to said yarn guide holding means and at its other end portion to said member, means on the member forming a bight in the flexible element, and means to move said bight-forming means bodily by uniform increments in a direction along said member in a direction to effect let-off of said flexible element from said movable member.

9. Winding mechanism for forming yarn packages comprising in combination with a constantly rotating yarn receiver and a yarn guide traversable lengthwise thereof, a traverse and gain controlling mechanism for the guide, said mechanism embodying a to and fro movable member having a to and fro stroke, a bell crank lever and a poker arm operatively connected to the latter and coöperating, connecting and governing devices on said member and between the same and said bell crank lever, the said devices comprising a flexible element operatively connected at one end portion to said bell crank lever and at its other end portion attached to said member at a fixed distance from the ends thereof, means on said member forming a bight in the flexible element, and means to move said bight forming means by increments during the building operation, toward the point of attachment of said flexible element to said movable member.

10. Winding mechanism for forming yarn

packages comprising in combination, a constantly rotating yarn receiver and a yarn guide traversable lengthwise thereof, a traverse and gain controlling mechanism for the guide, said mechanism embodying an actuator lever mounted transversely of the frame of the winding mechanism and having a to and fro stroke, yarn guide holding means and coöperating, connecting and governing devices on said lever and between the same and said means, the said devices comprising a flexible element operatively connected at one end portion to the yarn guide holding means and having its other end portion attached to said lever at a fixed distance from the pivot thereof, means on said lever forming a bight in the flexible element, and means to move said bight forming means during the building operation incrementally toward the point of attachment of the flexible element to said lever.

11. Winding mechanism for forming yarn packages comprising in combination, a constantly rotating yarn receiver and a yarn guide traversable lengthwise thereof, a traverse and gain controlling mechanism for the guide, said mechanism embodying an actuator lever mounted transversely of the frame of the winding mechanism and having a to and fro stroke, yarn guide holding means and coöperating, connecting and governing devices on said lever and between the same and said means, the said devices comprising a flexible element connected at one end portion to the yarn guide holding means and connected at its other end portion to said lever, means on said lever forming a bight in the flexible element, and means to move said bight forming means during the building operation, toward the open part of the bight.

12. Winding mechanism for forming yarn packages comprising in combination, a constantly rotating yarn receiver and a yarn guide traversable lengthwise thereof, a traverse and gain controlling mechanism for the guide, said mechanism embodying an actuator lever mounted transversely of the frame of the winding mechanism and having a to and fro stroke, yarn guide holding means and coöperating, connecting and governing devices on said lever and between the same and said means, the said devices comprising a flexible element operatively connected at one end portion to said yarn guide holding means and attached at its other end portion to said lever, means on the lever forming a bight in the flexible element, and means to move the bight forming means by uniform increments during the building operation, in a direction to effect let-off of the flexible element from said actuator lever.

13. Winding mechanism for forming yarn packages comprising in combination, a constantly rotating yarn receiver and a yarn

- guide traversable lengthwise thereof, a traverse and gain controlling mechanism for the guide, said mechanism embodying an actuator lever mounted transversely of the frame 5 of the winding mechanism and having a to and fro stroke, yarn guide holding means and coöperating, connecting and governing devices on said lever and between the same and said means, the said devices comprising 10 a flexible element operatively connected at one end portion to said yarn guide holding means and fixedly connected at its other end portion to said lever at a fixed distance from the pivot thereof, means on said lever forming 15 a bight in the flexible element, and means to move said bight forming means by increments during the building operation in a direction toward the point of connection of the flexible element with said actuator 20 lever.
14. Winding mechanism for forming yarn packages comprising in combination, a constantly rotating yarn receiver and a yarn guide traversable lengthwise thereof, a traverse and gain controlling mechanism for 25 the guide, said mechanism embodying an actuator lever having a to and fro stroke, a bell crank lever having an arm provided with a prolonged curved extension, a poker arm 30 operatively connected to said bell crank lever and coöperating, connecting and governing devices on said actuator lever and between the same and said bell crank lever, the said devices comprising a flexible element attached at one end portion to said bell 35 crank lever and adapted to be received by the said curved extension thereof, the opposite end portion of said flexible connection being attached to said actuator lever at a 40 fixed distance from the ends thereof, means on said lever forming a bight in the flexible element, and means to move said bight forming means incrementally during the building operation in a direction to effect let-off of the 45 flexible element from said actuator lever.
15. Winding mechanism for forming yarn packages comprising in combination, a constantly rotating yarn receiver and a yarn guide traversable lengthwise thereof, a traverse and gain controlling mechanism for the 50 guide, said mechanism embodying an actuator lever having a to and fro stroke, a bell

crank lever having an arm provided with a prolonged curved extension, a poker arm operatively connected to said bell crank lever, 55 and coöperating, connecting and governing devices on said actuator lever and between the same and said bell crank lever, the said devices comprising a flexible element operatively connected at one end portion to said bell 60 crank lever and adapted to be received upon the said curved extension thereof, the opposite end portion of said flexible connection being attached to said actuator lever at a fixed distance from the pivot thereof, means 65 on said actuator lever forming a bight in the flexible element, and means to move said bight forming means by uniform increments during the building operation in a direction toward the point of connection of said 70 flexible element with said actuator lever.

16. Winding mechanism for forming yarn packages comprising in combination, a constantly rotating yarn receiver and a yarn guide traversable lengthwise thereof, a traverse and gain controlling mechanism for the 75 guide, said mechanism embodying an actuator lever having a to and fro stroke, a bell crank lever having an arm provided with a prolonged curved extension, a poker arm 80 operatively connected to said bell crank lever and coöperating, connecting and governing devices on said actuator lever and between the same and said bell crank lever, the said devices comprising a flexible element connected at one end portion to said bell 85 crank lever and adapted to be received upon the said curved extension thereof, the other end portion of said flexible connection being attached to said actuator lever at a fixed 90 distance from the pivot thereof, means upon said actuator lever forming a bight in the flexible element and means to move said bight forming means by increments during the building operation, toward the open part 95 of said bight.

In testimony whereof, I have signed my name to this specification, in the presence of two subscribing witnesses.

JOHN V. CUNNIFF.
